CLAIM

The ornamental design for a stretchable animal leash, as shown and described.

DESCRIPTION

FIG. 1 is a perspective view of the stretchable animal leash of the present invention, the snap fastener and coupler link being shown in dashed line since they do not form part of the invention;

FIG. 2 is a handle-end elevational view of the leash;

FIG. 3 is a coupler-end elevational view thereof;

FIG. 4 is a right side elevational view of the leash, the left side view being identical thereto; and,

FIG. 5 is a top plan view of the leash, the bottom plan view being identical thereto.
